UNITED STATES PATENT OFFICE.

CHARLES H. MYERS, OF BUFFALO, NEW YORK.

CARBURETER FOR MOTOR-CYCLES AND OTHER PURPOSES.

1,075,596.

Specification of Letters Patent.

Patented Oct. 14, 1913.

Application filed February 24, 1910, Serial No. 545,775. Renewed March 7, 1913. Serial No. 752,786.

To all whom it may concern:

Be it known that I, CHARLES H. MYERS, a citizen of the United States, residing at Buffalo, in the county of Erie and State of New York, have invented a new and useful 5 Carbureter for Motor-Cycles and other Purposes, of which the following is a specification.

This invention relates to that class of motor cycles which are propelled by means of 10 an explosive engine, and has special reference to means for generating and supplying the combustible gas to the engine.

The invention has for its object the provision of simple and inexpensive means for generating the gas and preventing loss of the volatile fluid from which it is formed, while at the same time providing for a continuous supply of the gas.

20 These objects and such other incidental objects as will hereinafter appear, are attained by the use of the mechanism illustrated in the accompanying drawings, and the invention consists in certain novel features of the same which will be hereinafter first fully described and then more particularly pointed out in the appended claims.

In the drawings, Figure 1 is a perspective view of a generator constructed in accordance with my invention. Fig. 2 is a longitudinal vertical section of the same. Fig. 3 is a horizontal section taken partly through the reservoir or storage tank and partly through the gas generating compartment. Fig. 4 is a transverse vertical section. Fig. 5 is a detail perspective view of a portion of one of the wick holders. Fig. 6 is a detail perspective view showing a modified form of the invention. Fig. 7 is a trans-

40 verse vertical section of such modified form.

The body of the generator consists of an elongated casing or housing 1 provided with tapered ends, as indicated at 2 and 3, to the apexes of which are secured brackets or loops 4 by means of which the devices may be secured in position upon the frame of the machine. Near the tapered ends of the body I provide the internal partitions or end plates 5, thereby providing compartments 6 at the ends of the body of substantially triangular form which may be utilized for various purposes. In the drawings, I have shown one of these compartments as used to contain lubricating oil 55 which may pass through an outlet pipe 7

to the engine or to other parts of the vehicle in order to lubricate the bearings and insure an easy running machine. In order to utilize these end chambers, a plug 8 is fitted in the upper side of the same to permit the liquid to be poured thereinto. The space between the end plates 5 is divided by a horizontal partition 9 into an upper reservoir or storage tank 10 and a lower generating compartment 11, as will be readily understood. A filling opening 12 is provided in the top of the body and this filling opening is normally closed by a plug or screw cap 13 in order to permit a supply of volatile fluid to be poured into the tank, as will be readily understood. The user of the machine may be easily informed as to when the tank has been filled by reason of the fluid overflowing through the said opening. In the bottom of the partition 9 is an opening 75 through which the fluid may pass to the generating compartment, and this opening is normally closed by a stem 15 threaded in a bearing 16 in the top of the tank and equipped with an operating handle 17, as 80 shown and as will be readily understood. When charging the device, this stem 15 is raised so as to establish communication between the tank 10 and the generating compartment 11, and the gasoline or other hydrocarbon which is poured into the tank is then passed at once into the generating compartment. When the proper supply of the volatile fluid has been fed into the generating chamber, the stem 15 is turned inward so as 85 to cut off the flow into the said compartment and the subsequent feeding of the fluid will provide a reserve supply within the tank 10.

Within the generating compartment 11, I 95 arrange a series of superposed pans or wick holders 18 which are of a width slightly less than the width of the compartment and are disposed so as to provide a tortuous air passage between and over the several 100 pans and around the ends of the same. That is to say, the pans are arranged so that the space due to the difference in width between the pans and the compartment will be arranged alternately at opposite sides of the 105 pans. The side of the pan adjacent the said opening is lower than the opposite side of the pan, as indicated at 19, and this difference in height of the sides of the pans permits the air to pass from the space at 110

the side of the pan into the space between adjacent superposed pans and so across the surface of the wicks 20 arranged within the pans. These wicks are preferably short 5 lengths of woven wicking arranged on end transversely of the pans with their capillary passages vertically disposed. This arrangement presents the ends of the wicks to the passing air currents and utilizes the force 10 of capillary attraction to bring to the surface every particle of the oil or other fluid with which the wicks have been saturated. It is to be understood, however, that this particular form of oil-holding material is 15 not essential to the operation of the generator, although most satisfactory results have been obtained therefrom, and that any absorbent material may be used with good effect.

20 In order to prevent the air current passing over the wicking from sucking the same from its position within the pan, I provide a series of longitudinal rods 21 secured rigidly to the ends of the pans and passing over 25 the wicking so as to securely hold the same within the pans. The pans are each supported by the next lower pan, and in order to acquire the necessary strength without undue weight, I provide within each pan a 30 series of transverse partitions 22 which are preferably constructed of perforated corrugated sheet metal plates set on edge within the pans and rising to the full height of the ends of the same. These partitions conse- 35 quently serve to support the superposed pans and also serve to direct the air currents squarely across the surface of the wicking so as to thoroughly act on the entire body of volatile fluid. A longitudinal partition 40 23 is arranged within the body of the device near one side of the same so as to form an air flue 24 communicating with the atmosphere and having an open lower end near the bottom of the body. As shown 45 most clearly in Fig. 4, this air flue leads directly to and upon the lowest pan or wick holder, which is of the full width of the body of the device so as to extend entirely 50 across the same. The air is admitted to the air flue 24 through a series of openings 25 provided on the side of the device, which openings may be controlled by a screw cap or other device 26 and are preferably 55 equipped with a screen 27 so as to filter the air and prevent the entrance of dust and other deleterious matter to the generating compartment. The air is drawn through the said openings into the air flue by the suction of the engine and passes down to 60 the lowest pan or wick holder and transversely across the same, and then upward in a tortuous course over the successive superposed pans, escaping through an outlet pipe 28 which is preferably disposed slightly 65 above the uppermost wick holder or vaporiz-

ing pan and communicates with a small discharge chamber 29 formed by an offset 30 in the partition 9, the said chamber serving as a means for creating a vapor cushion which will receive the pulsations of the engine and prevent the same being transmitted to the wick holders so as to disturb the wicks and to that extent interfere with the successful generation of the gas. The gas passes through the pipe 28 to an air and gas mixer 31 equipped with a back-firing escape valve 32 and then passes through a pipe 33 directly to the explosive chamber of the engine. 70

In filling the generator, the oil is fed directly onto the wicks in the uppermost pan or wick holder and will saturate the same and then overflow onto the next lower pan, the wicks in which will be saturated, after which the surplus oil will overflow therefrom to the next lower pan, and this operation will be repeated until all of the wicks except those in the bottom pan have been saturated. As soon as the oil or other volatile fluid begins to pass into the wicks in the bottom pan, a dripping of the fluid through a stop-cock 34 depending from the bottom of the generator will be noticed and the operator then at once manipulates the rod 15 to cut off the flow and closes the valve 34 so as to prevent loss of the fluid, the pouring of the fluid, however, being continued until the storage tank or reservoir is full. The engine, having been started, air will be drawn through the generating compartment in the tortuous course described and will vaporize the oil at the surface of the several wicks, the vapor thus created being carried into the combustion chamber of the engine and there exploded to drive the 100 engine. Should the engine begin to work improperly or give notice of diminishing supply of vapor, the rod 15 is manipulated to permit a flow of the fluid from the storage tank 10 to the generating compartment 110 so as to replenish the supply therein, and the stopping of the engine is thus avoided. 110

It will be noted that the wicks in the bottom pan are not permitted to become saturated when the fluid is fed into the generating chamber but the feeding of the fluid is arrested as soon as a dripping from the bottom pan is noticed, and this dripping will occur as soon as any fluid is fed to the wicking therein, inasmuch as the drip-cock 34 depends from the bottom of the said pan. This bottom supply of wicking, however, serves to catch and hold any fluid which may be thrown from the upper pans by the vibration of the machine during its travel, 120 and the fluid thus caught and absorbed by the said wicks will be vaporized by the incoming air, as will be understood.

The form of generator heretofore described is adapted for ordinary motor cycle 130

travel. When a racing machine is to be equipped, however, I employ the construction illustrated in Figs. 6 and 7, in which the storage tank 10 is omitted and the wick holders 35 are arranged within the body 36 so as to occupy the entire interior of the same, and the longitudinal partition 37 projects slightly above the top of the body, as indicated at 38, a hood 39 being formed over the upper edge of the said partition and spaced therefrom as shown clearly in Fig. 7. The air inlet openings 40 are provided in the side of the said hood so as to admit air in large quantities to the air passage formed between the partition and the side of the body, which air will pass to and between the several wick holders, as indicated by the arrows in Fig. 7, so as to act on the entire body of the oil and generate a plentiful and constant supply of gas which is fed to the engine. In this form of the invention, the wicks are saturated to their fullest capacity so that a supply of gas equal to the heaviest demands of the engine will be quickly created and constantly maintained. Inasmuch as there is no storage supply of the hydrocarbon or other fluid in this form of the invention, there is no dead weight for the machine to carry, and, consequently, the desired maximum speed of the machine may be quickly attained.

From the foregoing description, taken in connection with the accompanying drawings, the advantages of the construction and of the method of operation will be readily apparent to those skilled in the art to which the invention appertains, and while I have described the principle of operation of the invention, together with the apparatus 40 which I now consider to be the best embodiment thereof, I desire to have it understood that the apparatus shown is merely illustrative, and that such changes may be made when desired as are within the scope of the 45 claims appended hereto.

I make no claim to features shown herein but claimed in my copending application Serial No. 545773, filed February 24, 1910, for carbureter for stationary engines and 50 other purposes.

Having thus described the invention, what I claim as new, and desire to secure by Letters Patent, is:—

1. A carbureter for motor cycles and other 55 purposes comprising an elongated casing having an air flue of substantially the same length as the casing and extending along one side thereof, a series of superposed holding devices for volatile liquid each elongated 60 in the direction of the length of the casing and provided with air directing channels extending transversely of said holding devices, the lowermost of said devices extending into the air flue with the corresponding 65 ends of the air channels of said lowermost

holding device also extending into the air flue; and an outlet for enriched air at the side of the casing remote from the air flue.

2. A carbureter for motor cycles and other 70 purposes comprising an elongated body or casing having at one side a longitudinally arranged partition of a length substantially that of the interior of the body and extending from the top of the body toward the bottom thereof but terminating short of the latter with the space between the partition and the adjacent side of the body constituting an air conduit, a holder for volatile liquid coextensive with the bottom of the body and underriding the air conduit 75 throughout the length thereof, said holder being provided with transverse partitions dividing the holder into a series of transverse air channels, which channels extend into the air conduit formed by the first 80 named partition, a series of superposed holders for volatile liquid arranged in staggered relation within the space between the partition and the opposite side of the body or casing and above the bottom of the holder, 85 the said superposed holders communicating at alternately opposite sides to provide a tortuous passage from the air conduit, an air inlet near the outer end of the air conduit, and an outlet for enriched air at the 90 side of the body remote from the partition and communicating with the passage above the uppermost holder for volatile liquid.

3. A carbureter for motor cycles and other 95 purposes comprising an elongated body or 100 casing having a longitudinally arranged partition near one side and of substantially the same length as the interior of the body, said partition extending from the top of the body toward the bottom thereof but terminating short of the latter, a holder for volatile liquid coextensive with the bottom of the body and underriding the partition and provided with means for dividing the air 105 passing thereover into a series of air currents movable transversely of the body, a series of superposed holders for volatile liquid above the bottom holder and arranged in staggered relation between the partition and the opposite side of the body, said holders 110 communicating at alternately opposite sides to provide a tortuous passage from the air conduit and each divided into a series of air channels, and an elongated chamber above and along one side of the topmost 115 of the holders for volatile liquid and in communication therewith, said chamber being provided with an outlet for the enriched air.

4. A carbureter for motor cycles and other 120 purposes comprising an elongated body with tapered ends, a partition within the body dividing the same into longitudinal chambers, controllable means for establishing and cutting-off communication between the 125 130

chambers, holders for volatile liquid in one chamber, each holder being provided with absorbent material for the volatile liquid and with partitions dividing the holder into numerous compartments for the absorbent material, and also constituting air channels, means for admitting air to the holders for volatile liquid, means for the escape of carbureted air after traversing said holders, and partitions in the body near the ends thereof for establishing chambers in said ends independent of the chambers formed by the first named partition.

5. A carbureter for motor cycles and other purposes comprising an elongated body with tapered ends, a partition dividing the body into chambers, one of which constitutes a storage chamber for volatile liquid, holders in the other chamber for volatile liquid, 10 said holders being provided with absorbent material and partitions dividing each holder into numerous air channels, controllable means for permitting the flow of volatile liquid from the storage chamber to the second named chamber, a division wall within the body member in spaced relation to one of the tapered ends and separating both chambers from the said tapered end of the body member to constitute a third chamber 20 for the storage of lubricant, and means for the introduction of lubricant into and its removal from the last named chamber.

6. A carbureter for motor cycles and other purposes provided with an elongated body 25 having tapered ends, cross partitions in said body, one at the junction of the body member with the corresponding tapered end and the other within the body member in spaced relation to the other tapered end, a longitudinal partition dividing the space between the cross partition into two chambers, another partition in spaced parallel relation to one side wall of the body to provide an elongated air flue opening into the bottom 35 of the lower end of the two longitudinal chambers, means for placing the two longitudinal chambers in communication at will, means for the introduction of air into the air flue, means for exposing volatile fluid to air currents within the lower one of the longitudinal chambers, means for the escape of carbureted air from said lower chamber, and means for the introduction and removal of lubricant from the chamber formed at 45 one end of the body member by the cross partition spaced therefrom.

7. A carbureter for motor cycles and other purposes comprising an elongated body or casing, a partition therein in spaced parallel relation to one side of the body member and extending from the top toward the bottom but stopping short thereof, another partition extending from the side of the body member remote from the first named partition to said first named partition and divid-

ing the body member into upper and lower compartments, the lower compartment communicating with the space between the first named partition and the side of the body member, means for establishing communication at will between the two compartments, superposed pans within the lower compartment, said pans being in staggered relation with the lowermost pan extending beneath the first named partition, said pans communicating at alternately opposite ends each with the next higher pan, absorbent material in each pan having its exposed surface stopping short of the top of the pan to provide a free tortuous air passage over all the pans in order, an air inlet to the space between the first named partition and the adjacent wall of the body member, and an outlet for carbureted air communicating with the topmost pan of the series.

8. The combination of an elongated casing, a partition therein dividing the casing into two chambers, said partition having an offset at one side into one chamber to form an elongated duct in the other chamber, said duct having an outlet leading from the casing, an elongated air flue at the opposite side of the casing of substantially the same length as the casing and leading into the chamber having the duct formed by the offset of the partition, a series of oil holding devices within the chamber provided with the air flue and duct, and means in said oil holding devices for directing air in streams therethrough from the inlet air flue to the 100 outlet for the elongated duct.

9. The combination of a casing, a series of superposed wick holding pans within the casing, alternate pans having their opposite sides spaced from the corresponding sides of the casing and of less height than the other sides of the pans, wicks in each pan and equal in height to the lower end of the pan, there being a free space between the exposed surface of the wick and the upper edge of the pan, means for supplying a volatile liquid to the wicks, means for admitting air to flow over the wicks of the pans in successive order, and means for drawing off the gas laden air.

10. The combination of an elongated casing having a longitudinally disposed partition therein of substantially the same length as the interior of the casing, said partition forming a flue between it and the adjacent side of the casing and terminating short of the bottom of the casing, an air inlet communicating with the upper end of said flue, an oil holder extending the full width and length of the body and arranged 125 on the bottom thereof in communication with the bottom of said flue, said oil holder having a series of air directing channels extending transversely of the casing and all opening at one end into the air flue formed 130

by said partition, an outlet for gas-charged air, and a series of superposed oil holding devices arranged above the first named oil holder and presenting a tortuous passage 5 from the air flue to the outlet for carbureted air.

In testimony, that I claim the foregoing

as my own, I have hereto affixed my signature in the presence of two witnesses.

CHARLES H. MYERS.
